UNITED STATES PATENT OFFICE

HERMAN S. JOHNS, OF ADA, OKLAHOMA

SCRAPER-BLADE ATTACHMENT FOR BROOMS

Application filed October 9, 1928. Serial No. 311,348.

This invention comprehends the provision of a scraping blade attachment for brush brooms, the attachment being very simple in construction and designed to be quickly and 5 conveniently associated with the broom or removed therefrom as the occasion may require.

In carrying out the invention I contemplate an attachment of the above mentioned 10 character which is formed from a single piece of material shaped to conform to the configuration of the head of the broom and held associated therewith without the use of additional fastening elements such as nails, 15 screws or the like.

An important object of the invention resides in the provision of a scraping blade attachment comprising a plate adapted to 20 repose upon the head of the brush and formed with an integral plate and bendable prongs 25 adapted to be embedded in said head to assist in holding the attachment associated with the brush, the handle of the latter being also employed to cooperate with the bendable prongs for holding the attachment immovably positioned upon the head.

A further object of the invention resides in the provision of an attachment of the class 30 in question which is designed to accommodate itself with different size brushes.

Other objects and advantages will appear when the following detail description is read in connection with the accompanying drawing, the invention residing in the construction, combination and arrangement of parts 35 as claimed.

In the drawing forming part of this application like numerals of reference indicate similar parts in the several views and where- 40 in:

Figure 1 is a view of a brush broom showing the invention associated therewith.

Figure 2 is a transverse sectional view therethrough.

Figure 3 is a fragmentary detail sectional view showing how the broom handle is employed to assist in holding the attachment associated with the head of the broom.

Figure 4 is a plan view of the attachment. 50 Referring to the drawing in detail 10 in-

dicates the head of a brush broom of ordinary well known construction, the upper surface of which is curved as illustrated, while the head 10 is provided with a threaded opening to accommodate the handle 11. The handle is provided with a reduced threaded extremity 12 adapted to be screwed into the opening in the head 10, and this reduced extremity of course provides the handle with a shoulder 13, the purpose of which will be 55 hereinafter described.

The attachment comprises a plate 14 which may be constructed from any suitable material, preferably thin high grade steel, and which plate is preferably of the outline 60 illustrated in Figure 4. In other words the plate is formed with a relatively wide portion adapted to extend across the head 10 for an appreciable distance, and also formed with a reduced narrow portion extending in the 65 direction of the handle 11 when the attachment is associated with the brush head. This reduced portion 15 is provided with a slot 16 of a size to receive the reduced threaded exten- 70 sion 12 of the handle 11, and when the plate is associated with the head 10, the slot 16 registers with the opening in the brush head, so that the handle can be passed through the slot and screwed into said opening. However, the size of the opening is less 75 than the diameter of the handle 11, so that when the reduced extremity 12 is screwed into the opening in the head 10, the shoulder 13 of the handle reposes upon the plate 10 at opposite sides of the slot 16 thereby im- 80 pinging the plate between the head 10 and the shoulder 13 to assist in holding the attachment fixed relatively to the broom. By reason of the slot 16, it is manifest that the attachment may be used with different size 85 brushes, that is to say that the attachment can be associated with the brush wherein the handle 11 is located on the head in a different position from that illustrated in the accom- 90 panying drawing. The relatively wide portion of the plate is slit along spaced parallel lines as at 17, and the separated portion defined by said slits is then offset to provide a 95 blade 18 as clearly illustrated in Figures 1 and 2. The plate in its entirety is curved to 100

conform to the curvature of the head 10, while the plate is further formed with bendable pointed prongs 19 which extend an appreciable distance beyond the blade 18 as clearly illustrated. These prongs are adapted to be bent downwardly below the cutting edge of the blade, thence extended inwardly beneath the head of the brush, and finally have their pointed extremities driven upwardly into the head 10 as illustrated in Figure 2. Manifestly the prongs 19 and the handle 11 cooperate to hold the attachment fixed relatively on the head of the broom and at the same time permits the attachment to be quickly and conveniently associated with the broom, or removed therefrom as the occasion may require, as for instance when it is desired to remove the attachment from a worn broom and associate it with a new one. As above stated the attachment is very simple in construction and can be manufactured and sold at a nominal cost.

While it is believed that from the foregoing description the nature and advantages of the invention will be readily understood, I desire to have it known that I do not limit myself to what is herein shown and described and that such changes may be resorted to when desired as fall within the scope of what is claimed.

What is claimed is:

1. A scraping blade attachment for brooms comprising a plate curved longitudinally to accommodate itself to the head of the broom upon which it is adapted to repose, a blade formed on one edge of the plate and offset with relation thereto, and means including bendable prongs arranged at the opposite sides of the blade and adapted to be embedded in the end face of the head of the broom for holding the plate fixed relatively to said head.
2. The combination with a broom having a head formed with an opening therein, and a handle having a reduced threaded extremity adapted to be screwed into said opening, of a scraper blade attachment comprising a plate shaped to conform to the configuration of said head upon which the plate is adapted to repose, said plate having a longitudinal slot adapted to register with said opening and through which the handle is adapted to be passed, whereby said handle impinges the plate therebetween and said head to assist in holding the plate associated with the broom, a blade formed on said plate and offset with relation thereto, and bendable prongs carried by the plate at opposite ends of the blade and adapted to be embedded in the under side of the head to assist said handle in holding the attachment fixed relatively to the head.

In testimony whereof I affix my signature.
